UNITED STATES PATENT OFFICE.

HOBART A. HALLOWELL, OF WOODLYNNE, AND EDWARD D. HALLOWELL, OF AUDUBON, NEW JERSEY.

VENTED ELECTRIC SOCKET.

Application filed July 8, 1925. Serial No. 42,326.

The object of our invention is to devise a novel construction of a vented electric socket in which provision is made to permit the circulation of air at all times through 5 the socket in order to prevent the overheating of the socket.

With the above in view, our invention comprehends a novel construction and arrangement of a vented electric socket.

10 It further comprehends a novel construction of an electric socket wherein the shell, cap, insulating member and portions which receive the base of the plug is constructed in a novel manner.

15 Other novel features of construction and advantage will hereinafter more clearly appear in the detailed description and the appended claims.

For the purpose of illustrating the invention, we have shown in the accompanying drawing a typical embodiment of it, which, in practice, will give reliable and satisfactory results. It is, however, to be understood that this embodiment is typical only 25 and that the various instrumentalities of which our invention consists can be variously arranged and organized, and that the invention is not, therefore, limited to the precise arrangement and organization of these 30 instrumentalities as herein set forth.

Figure 1 represents a front elevation of a vented electric socket embodying our invention.

35 Figure 2 is a top plan view of the socket. Figure 3 is a bottom plan view of the socket.

Figure 4 is a top plan view of the porcelain.

Similar numerals of reference indicate corresponding parts.

Referring to the drawings:

1 designates a vented electric socket, embodying our invention. The socket consists of a sleeve 2 having the upper enlarged portion 3, which merges into the lower portion 4, which is of reduced diameter. 5 designates the cap which is secured to the sleeve 2 in any desired manner, and which is provided with the apertures 6.

50 7 designates the porcelain or insulating body, which is provided in the usual manner with the electric connections, and also with the recesses or apertures 8 which when the

parts are assembled are in alignment with the apertures 6 of the cap.

9 designates a threaded sleeve secured to the porcelain in any desired or conventional manner. This sleeve is outwardly deflected to form a plurality of rounded portions 10 which form a plurality of circumferentially spaced air passages 12. The portion 4 of the sleeve 2 which is of lesser diameter is outwardly deflected, as at 2, to surround the deflected portions 10 of the sleeve 9. When the parts are assembled, the air passages 12 will register with the apertures 6, so that a plurality of circumferentially spaced passages are formed, which extend longitudinally through the socket to permit the air to circulate therethrough, and thus retain the 70 socket in a cooled condition.

Our present invention can be economically manufactured and has marked advantages over the ordinary type of socket employed, since there is no danger of the socket becoming overheated with consequent injury to the conductors, or insulation or to any parts with which the socket may come into contact.

Having thus described our invention, what we claim as new and desire to secure by Letters Patent, is:

1. An electric socket having an insulating body having longitudinally extending recesses, and a sleeve secured to said body and deflected to form with the walls of said recesses ventilating passages.

2. An electric socket, comprising a sleeve having passages therethrough, an insulating body having apertures to register with said passages, and a cap connected with said sleeve and having apertures through it to register with the passages in said insulating body.

3. An electric socket, comprising a sleeve of reduced diameter at its forward end and having its wall deflected to form passages which extend through the rearward end of the sleeve, an insulating body having apertures to register with said passages, a threaded sleeve carried by said insulating body, and a cap having apertures to register with the apertures in said insulating body.

HOBART A. HALLOWELL.
EDWARD D. HALLOWELL.
